Patented Aug. 17, 1971

221,433

SAUNA HEATER

Albert F. Erickson, Arlington Heights, and Linas Burys,
Chicago, Ill., assignors to Air Xperts Corporation,
Chicago, Ill., and Sauna Corporation of America,
Chippewa Falls, Wis., fractional part interest to each

Continuation of design applications Ser. No. 15,467 and
Ser. No. 15,468, both Jan. 23, 1969, both now abandoned. This application June 11, 1969, Ser. No. 17,768

Term of patent 14 years

Int. Cl. D23—03

U.S. Cl. D23—84

FIG. 5

FIG. 4

FIG. 6

FIG. 1 is a front elevational view of a sauna heater embodying the new design;

FIG. 2 is a top plan view of the sauna heater as shown in FIG. 1;

FIG. 3 is a front perspective view looking downwardly from above the sauna heater shown in FIG. 1;

FIG. 4 is a front elevational view of the sauna heater embodying a modification in the new design;

FIG. 5 is a top plan view of the sauna heater as shown in FIG. 4; and

FIG. 6 is a front perspective view looking downwardly from above the sauna heater shown in FIG. 4.

The mesh-like areas on the drawing represent expanded metal.

This application is a combined continuation application of co-pending applications Ser. No. D. 15,467 and D. 15,468, filed Jan. 23, 1969, and now abandoned.

We claim:

The ornamental design for a sauna heater, as shown and described,
